ATTORNEY

UNITED STATES PATENT OFFICE.

FRANCIS I. HEMINGWAY, OF BRIDGEPORT, CONNECTICUT.

CURTAIN-FIXTURE.

1,323,692.

Specification of Letters Patent.

Patented Dec. 2, 1919.

Application filed September 18, 1916. Serial No. 120,749.

To all whom it may concern:

Be it known that I, FRANCIS I. HEMINGWAY, a citizen of the United States, residing at Bridgeport, in the county of Fairfield 5 and State of Connecticut, have invented certain new and useful Improvements in Curtain-Fixtures, of which the following is a specification.

The invention has reference generally to 10 improvements in curtain and shade fixtures; and, the invention relates, more particularly to a novel combined curtain pole and shade bracket.

The invention has for its principal object 15 to provide a combined curtain and shade bracket, which will eliminate the use of separate brackets and also, lessen the damage to the woodwork of a building, due to the attaching of the brackets thereto.

20 Still further, the invention includes a novel arrangement of shade supporting brackets; a plurality of pairs being provided, one of which are removably mounted, thereby, permitting the same to be readily 25 detached when not in use, thus, providing a construction, whereby, two shades may be supported in operative position, it being well known in the art, that shades of different color and weight are used during the various 30 seasons.

Among the other aims and objects of the invention may be recited, the provision of a device of the character mentioned with a view to compactness, and in which the 35 number of parts are few, the construction simple, the cost of production small, and the efficiency and operation high.

Other and further improvements and novel details in the construction and arrangement of parts will be appreciated from the description that follows, which for a clear understanding of the invention should be considered in connection with the accompanying drawings, forming a part hereof 45 and wherein the preferred embodiment of the invention is shown for the purpose of illustration.

The invention is clearly illustrated in the accompanying drawings in which;

50 Figure 1 is a side elevation of my improved bracket, showing a shade roller supported thereby.

Fig. 2 is a top plan thereof, showing a plurality of shade rollers supported in operative position, together with a curtain or drapery supporting pole.

Fig. 3 is a detail in side elevation of the fixedly and removably mounted shade bracket and,

Fig. 4 is a detail in side elevation of the 60 fixedly mounted shade bracket.

Similar characters of reference are employed in all of the above described views, to indicate corresponding parts.

Referring now, more specifically to the 65 several figures of the said drawings, it may be here noted that the brackets as constituting the several pairs employed in the present invention are identical in construction, with the exception that certain thereof are provided with squared trunnion receiving openings while the remaining have arranged therein the usual rounded trunnion receiving openings. Hence, reference will be had to but one bracket of the several pairs, in 70 the description that follows. The present construction may be said to embody an immovable bracket, indicated in its entirety by the numeral 1 and comprising a base plate 2 the same having formed therein, a plurality of openings 3 whereby securing screws 4 may be passed therethrough and the bracket thereby, fastened in the desired position. A supporting arm 5 is formed upon one side of the base plate 2 and bent at substantially right angles thereto, thus, providing 75 for the necessary shade roller trunnion receiving means. The outer portion of the supporting arm 5 is depressed, as at 6, to form a substantially concavo-convex element, which, has arranged therein, a diagonally disposed rectangular slot 7, which is adapted to receive therein the squared bearing trunnion of a shade roller. To provide 80 for means whereby the removably supported 85 bracket may be received and maintained in proper position upon the immovable bracket 1 the outer extremities of the latter are slotted at 8 and a free portion of the arm 5 is then bent outwardly or offset, to constitute a 90 guiding and supporting finger 9, while that portion of the arm 5, as in proximity to the base plate 2, has formed therein, an opening 10, the purpose of which will be presently 95 apparent.

100 In referring to the removable shade bracket, I shall, for the purpose of convenience, indicate the same in its entirety by the numeral 11, the bracket comprising a strip of bendable metal, the outer portion of 105 which is depressed, thus, providing a concavo-convex portion 12, similar to the por-

tion 6, and has also formed therein a diagonally disposed rectangular pocket or slot 13, whereby, the squared bearing trunnion of a second shade roller may be received therein. A recess 14 is formed within the bracket 11, preferably intermediate the ends thereof and is engaged by the offset supporting finger 9, when the bracket 5 is carried upon the immovable bracket 1. Upon the rear 10 extremity of the bracket 11, there is arranged an offset finger 15, the same being adapted to be engaged with the openings 10 of the immovable bracket, consequently, providing for means whereby the removable bracket will be securely fastened thereupon.

With a view toward providing for means whereby the conventional form of U-shaped curtain pole, as indicated by the numeral 16 may be also supported by a bracket, a 20 plurality of cylindrical sleeves 17 are secured to the outer faces of the base plate 2, by soldering, welding or the like and are adapted to receive thereinto the lateral extremities of the supporting pole 16. As will be noted, the curtain pole 16 when in position is arranged within the same horizontal plane as that in which the immovable and removable brackets 1 and 11 respectively, are arranged. By this arrangement, the 30 shade rollers supported by the said brackets will be hidden from view when the curtain or other drapery is arranged about its respective pole 16.

The operation of the device may be reviewed as follows:

A plurality of the immovable brackets 1 carrying thereupon the cylindrical sleeves 17, are secured to a window frame by means of the screws 4. It is to be understood, that 40 the supporting arms 5 of each of these brackets have arranged therein, the usual squared and rounded trunnion receiving openings, whereby the complementally formed trunnions of the shade roller 18 may be received thereby. Due to the concavo-convex arrangement of the portions 6, the outer extremities of the shade roller supporting trunnion will be permitted to lie flush with the outer surface of the supporting arms 5. The removable brackets 11 are then engaged with the supporting arms 5 of the immovable brackets, the offset fingers 15 thereof being engaged with the openings 10 of the said supporting arms and the recesses 14 engaged with the offset supporting fingers 9, arranged upon the outer ends of the supporting arms 5. By arranging the intermediate portions of the brackets 11 between the offset fingers 9 and the supporting arms 5, it is obvious that undue lateral movements of the brackets 11 will be prevented. The concavo-convex portions 12 of the brackets have arranged therein, the squared and rounded bearing openings, 65 whereby the trunnions of the shade roller

19 will be received thereby. It is to be also noted, that the said concavo-convex portions 12, compensate for the increased distance between the removable brackets, thereby, permitting a pair of shade rollers of corresponding length to be used. With the shade roller supporting brackets thus positioned, the curtain supporting pole 16 is engaged with the cylindrical sleeve 17 in the manner hereinbefore set forth, the curtain 75 or other drapery having been previously arranged thereon. Should the device be used for supporting a single shade roller, the removable bracket 11 may be readily disengaged from the supporting arm 5 of the immovable bracket and the latter used to support the desired shade roller.

Instead of using a solid curtain supporting pole, as shown in the preferred embodiment of the invention, it is apparent that conventional form of telescopic pole may be substituted therefor; furthermore, that the cylindrical sleeve 17 may be dispensed with and the usual hooked curtain pole supporting brackets equally well adapted for the 80 desired purpose.

Still further embodiments of the invention and those herein especially defined may be resorted to as conditions or preference may dictate, as may be in keeping with the 95 hereto appended claims.

I claim:

1. A curtain fixture comprising a base plate, a shade supporting arm rigidly extended therefrom, said arm being equipped with an opening in proximity to the base, said arm having a vertical offset finger on the end thereof, said arm being equipped with a shade roller securing slot or opening, a removable shade supporting arm having its intermediate portion received by said offset finger, one end of said removable arm being equipped with an offset finger to be engaged in said opening in said rigid arm in proximity to said base, and the outer end of said removable arm being equipped with a shade roller receiving slot for the purpose set forth.

2. A curtain fixture comprising a base plate, a shade supporting arm rigidly extended therefrom, said arm being equipped with an opening in proximity to the base, said arm having a vertical offset finger on the outer end thereof, a portion of said arm being formed with a laterally extending depression, which forms a concavo-convex portion, said portion being equipped with a shade roller receiving slot or opening, a removable shade supporting arm having a recess in its lower edge to be received by said offset finger, one end of said removable arm being engaged by the face of the rigid arm to cover said depression, and equipped with an offset finger to be engaged in said opening in said rigid arm in prox-

imity to said base, and the outer end of said removable arm being equipped with a shade roller receiving slot for the purpose set forth.

5 3. A curtain fixture including a pair of plates, each comprising a base, a shade supporting arm extended from the inner edge of said base, a socket extending horizontally from the center of said base and arranged 10 beside and in the same horizontal plane as the shade supporting arm, and a U-shaped curtain pole having its lateral extremities re-

ceived in said sockets and arranged in the same horizontal plane with the supporting arm whereby the sockets and the curtain 15 pole will hide the shade roller arms from view.

In testimony whereof I affix my signature in presence of two witnesses.

FRANCIS I. HEMINGWAY.
